DISPLAY BOARD

Herbert H. Krueger, Chicago, Ill., assignor to Advertising Metal Display Co. Inc., Chicago, Ill., a corporation of Illinois

Application October 2, 1933, Serial No. 691,821

11 Claims. (Cl. 211—87)

This invention relates to improvements in display boards and it consists of the matters herein-after described and more particularly pointed out in the appended claims.

5 The boards, with which my invention is more particularly concerned, are especially adapted for the display of articles best presented while in a suspended condition and battery cables, ignition cables, etc. such as found in automobile 10 service stations and accessory establishments, are mentioned as typical articles.

Heretofore in displaying such articles for sale, it was the practice to provide a sheet metal panel to the rear face of which a wood frame was secured and into which there was screwed from the front of the panel, the desired number of cable suspending hooks or hangers. This type of display board had several objections. There were several parts to the complete board so that the 20 board was not only costly to produce but eventually the wood included therein, would dry out and crack. Therefore such a structure was not well adapted to sustain the heavy load of battery cables, ignition cables and the like, displayed thereon.

25 One of the objects of the present invention, is to provide a display board of this kind which does not require wood in its structure and wherein the associated hangers may be readily inserted and quickly and easily locked in place without the aid of tools of any kind.

Another object of the invention is to provide a novel means for detachably securing the hangers in position so that the thrust produced by the 35 supported load is not taken merely by the thin wall of the panel, but is distributed over a considerable area by means carried on the back of the panel and which means may be swung into and out of locking engagement with the hangers.

40 A further object of the invention is to provide a display board of this kind wherein the parts thereof may be arranged in a compact knock-down condition, convenient for shipment.

The above mentioned objects of the invention 45 as well as others, together with the many advantages thereof, will more fully appear as I proceed with my specification.

In the drawing:

Fig. 1 is a perspective view of a display board 50 of this kind, embodying the preferred form of my invention.

Fig. 2 is a fragmentary perspective view on an enlarged scale, relative to the scale of Fig. 1, of a part of the board as observed from the rear, showing at one place a hanger locked in the as-

sembled position by an associated locking element and also showing another of such elements in a position permitting the insertion or removal of the associated hanger.

Fig. 3 is a view in rear elevation, showing the position of the various parts when in disassembled relation for shipment.

Fig. 4 is a detail horizontal sectional view on a somewhat enlarged scale as taken on the line 4—4 of Fig. 2.

In general, my improved display board, which is made entirely of metal, includes a rectangular sheet metal front or panel having a rearwardly extending rim or flange to give it stiffness and depth. The flange associated with bottom edge 15 terminates in an upturned shoulder. In the top portion of the panel, openings are provided through which screws or other fastening devices may be inserted to secure the display board to a wall or other surface.

The front or panel is provided along its bottom edge with a plurality of holes and associated with each pair of these holes is a U-shaped hanger. The hangers are each inserted or assembled in place from the rear of the panel with the parallel 25 legs of each hanger extending forwardly through each of the two adjacent holes. The legs terminate at their front ends in upturned projections to prevent the cables or other articles suspended thereon from slipping therefrom.

The cross member of each hanger, when in its assembled position, engages the bottom flange shoulder. On the back of the panel, and associated with each hanger, is mounted a locking element. The locking element may be moved 30 into a position to not only hold the cross member against the shoulder but also to hold the rear ends of the parallel legs down against the bottom flange. With such an arrangement, the load of the displayed articles is distributed over a very 35 considerable area so that the tilting or tipping thrust of the hangers is not all imposed upon the thin sheet metal of the panel.

Referring now in detail to that embodiment of the invention, illustrated in the accompanying 40 drawing:

I indicates as a whole the sheet metal front or panel of the display board which is preferably of rectangular shape and has rearwardly extending, integral, top, bottom and end flanges 2, 3 and 4—4 respectively to not only stiffen the panel but to give it the desired depth. The bottom flange is formed to include an upstanding shoulder 5 which extends the full length of the flange,

to coat therewith and with the bottom part of the panel in providing a channel 6.

Near each top corner of the panel is a hole 7 through which screws (not shown) may be inserted to hold the board as a whole in operative relation upon a wall or other supporting surface. Along the bottom margin of the panel 1, just above the bottom flange 3 a plurality of spaced openings 8 is provided.

Associated with each two of said openings is a hanger 9 made of a relatively heavy stiff wire of a diameter approximating that of the holes 8. Each hanger, which is substantially U-shaped, includes parallel side legs 10—10 connected together at one end by a cross portion 11, the other end of each leg being turned upwardly as at 12. The side legs of each hanger are spaced apart a distance approximating that between two associated adjacent holes 8.

On the rear side of the panel, and positioned midway between the holes of two adjacent holes 8, is a hanger locking member 13. This member is in the form of a short piece of channel stock that includes side flanges 14—14 and a connecting web 15, the side flanges 14 having a depth approximating that of the flange 3 before mentioned.

Each member 13 is pivotally secured at the top end of its web 15 to the rear surface of the panel 1 by means of a rivet 16. In the bottom corner of the free margin of each flange is provided a notch 17, the purpose of which will soon appear. It is apparent that by means of the structure just above described, each member 13 may be swung about its pivot 16, in the plane of panel, from a position wherein said members stand upright, and parallel with the end flanges 4 to a position inclined with respect thereto, as best shown in Fig. 2. When the member 13 stands in the upper right position the bottom edge of its web and flanges, substantially engages upon the top surface of the bottom flange 3.

To assemble the hangers 9 in place, each locking element 13 is swung into an inclined position as best shown at the left hand end of Fig. 2. Thereafter the upturned ends of each hanger 9 are inserted through two adjacent holes 8 from the rear side of the panel and the hanger is then pushed forwardly until the cross member 11 thereof can drop down in front of the shoulder 5 of the flange 3. The associated member 13 is then swung downwardly about its pivot 16 so as to stand in the upright position. The notches 17 will then engage not only a top portion of the cross portion 11 of the hanger but also against an inside portion thereof. The hanger is thus securely held in place locked in position in the manner just described.

When all of the hangers have been assembled and the associated members 13 have been swung into the upright position mentioned, the notches 17 thereof so engage the cross bar 11 of each hanger as to prevent it from not only swinging upwardly but also to prevent it from moving forwardly, the shoulder 5 preventing a rearward movement of said cross bar.

In Fig. 1, I have shown as the article displayed, a battery cable 18 having an eye-like terminal 19 at one end engaged upon one of the hanger legs. It will be understood that a considerable number of such cables or similar articles will be suspended from the various hangers. It is apparent therefore, that a considerable weight is imposed upon the legs of the hangers which tends to tip the hanger about the holes 8 as an axis.

This tipping tendency, however, is counteracted or resisted by the engagement of the notches 17 in the members 13 with the cross bars 11. Thus, each hanger is securely locked in position until it is desired to remove the same. When it is so desired to remove a hanger, its associated member 13 is swung into the angular or inclined position shown at the left hand end of Fig. 2. The cross member 11 may now be lifted up from in front of the shoulder 5, so as to clear the same when the hanger may be withdrawn rearwardly from the panel.

The board as a whole is adapted for shipment in knock-down condition at which time the various hangers 9 may be enclosed in a draw string bag 20 as shown in Fig. 3 and this bag may be placed upon the rear side of the panel. Thus the parts of the board will make a neat rectangular package for shipment, and which package will correspond in shape and size to the panel and its flanges. In this condition the kits or knock-down boards may be compactly stacked for storage.

The board though light in weight, is strong and rigid because the parts are so formed and correlated as to mutually coat in their bracing effects. Furthermore the parts may be quickly assembled and disassembled without the aid of tools of any kind.

While in describing the invention, I have referred in detail to the form, arrangement and construction of the various parts thereof, the same is to be considered only in the illustrative sense so that I do not wish to be limited thereto except as may be specifically set forth in the appended claims.

I claim as my invention:

1. A display board embodying therein a panel having an opening therein, a hanger member positioned in said opening and having a portion extending rearwardly thereof, and a member operatively connected to the rear side of the panel for movement in a plane parallel to the plane of the panel into positions either to engage the rearwardly extending portion of the hanger and hold the hanger firmly in position or to release said portion to permit of the removal of the hanger from the panel.

2. A display board embodying therein a panel having an opening therein, a hanger including a portion adapted to be inserted through said opening and a part arranged at an angle to said portion, and a member operatively connected to the rear side of the panel for movement in a plane parallel to the plane of the panel into positions either to engage and confine said hanger against movement in the direction of the length thereof and against rocking movement or to release said hanger for removal from the panel.

3. A display board embodying therein a panel having an opening therein, a shoulder spaced to the rear of the panel, a hanger including a leg adapted to be inserted through said opening and a part arranged at an angle to said leg and adapted to engage against said shoulder, and a member operatively connected to the rear side of the panel for movement in a plane parallel to the plane of the panel into positions either to hold said hanger part against said shoulder and against an upward movement or to release said hanger part to permit the removal of the hanger from the panel.

4. A display board embodying therein a panel having an opening therein, a hanger including a leg adapted to be inserted through said opening from the rear of the panel and a part arranged

at an angle to said leg, and a member pivotally mounted on the rear side of the panel and swingable in a plane parallel to the plane of the panel into a position to engage and confine said hanger part against movement in the direction of the length of the leg and against an upward movement.

5. A display board embodying therein a panel having an opening therein, a shoulder spaced to 10 the rear of the panel, a hanger including a leg adapted to be inserted through said opening and a part arranged at an angle to said leg and adapted to engage against said shoulder, and a member pivotally mounted on the rear side of 15 the panel and swingable into a position to hold said hanger part against said shoulder and against an upward movement.

6. A display board embodying therein a panel having an opening therein, a hanger including 20 a leg adapted to be inserted through said opening and a part arranged at an angle to said leg, and a member mounted on the rear side of the panel and having a recess in one end, said member being movable into a position so that its 25 recess engages said hanger part and confines the same against movement in the direction of the length of the leg and against an upward movement.

7. A display board embodying therein a panel 30 having two openings therein and a rearwardly spaced shoulder, a hanger comprising legs adapted to be inserted through said openings and a member connecting the rear ends of said legs together, and a member pivoted on the rear 35 side of the panel and swingable into a position to engage and confine said connecting member against said shoulder and against an upward movement.

8. A display board embodying therein a panel 40 having an opening therein, a hanger including a leg adapted to be inserted through said open-

ing and a part arranged at an angle to said leg, a channel-like member mounted for movement on the rear side of the panel and having laterally spaced flanges each with a recess therein and which recesses when said member has been moved into one position are adapted to partially embrace and to confine said hanger part in the desired position.

9. A display board embodying therein a panel 10 having a rearwardly extending bottom flange that terminates in an upturned shoulder spaced rearwardly from said panel, said panel having a hole therein above said flange, a hanger having a leg extending through said opening and having an angular part engaged against said shoulder, and means for securing said angular part in position against said shoulder.

10. A display board embodying therein a panel 20 having a rearwardly extending bottom flange that terminates in an upturned shoulder spaced rearwardly from said panel, said panel having a hole therein above said flange, a hanger having a leg extending through said opening and having an angular part engaged against said shoulder, and a member mounted on the rear side of the panel and movable into a position for securing 25 said angular part in position against said shoulder.

11. A display board embodying therein a panel 30 having a rearwardly extending bottom flange that terminates in an upturned shoulder spaced rearwardly from said panel, said panel having a plurality of holes therein, a hanger having a plurality of legs each extending through an associated hole and connected together at the rear ends by a cross member engaged against said shoulder, and a member mounted on the rear side of the panel and movable into a position securing said cross member against said shoulder.

HERBERT H. KRUEGER.
